United States Patent

Des. 241,740

Patented Oct. 5, 1976

241,740

RADIATION SENSITIVE ELECTRONIC FLASH UNIT

Moto Shimano, Van Nuys, Calif., assignor to Opticon
Research & Development Corporation, Santa Monica,
Calif.

Filed Dec. 13, 1974, Ser. No. 532,719

Term of patent 14 years

Int. Cl. D16—05

U.S. CL. D16—42

FIG. 1.

FIG. 2.

FIG. 3.

FIG. 4.

FIG. 1 is a front perspective view of a radiation sensitive electronic flash unit showing my new design;
FIG. 2 is a side elevational view thereof;
FIG. 3 is a rear elevational view thereof; and
FIG. 4 is a bottom plan view thereof.

The grid texture partially shown in FIGS. 1 and 2 represents an overall pattern.

I claim:

The ornamental design for a radiation sensitive electronic flash unit, as shown and described.
